(57) **CLAIM**

The ornamental design for a rasp carrier, as shown and described.

DESCRIPTION

FIG. 1 is a perspective view of the rasp carrier.
FIG. 2 is a side elevation view of the rasp carrier of FIG. 1.
FIG. 3 is a front elevation view of the rasp carrier FIG. 1.
FIG. 4 is a back elevation view of the rasp carrier of FIG. 1.
FIG. 5 is a top plan view of the rasp carrier of FIG. 1.
FIG. 6 is a bottom plan view of the rasp carrier of FIG. 1; and,
FIG. 7 is the perspective view of FIG. 1 showing a rasp positioned on the carrier.
The broken lines are for illustrative purposes only and form no part of the claimed design.
